UNITED STATES PATENT OFFICE.

JOHN H. G. ZUNNER, OF ROCHESTER, NEW YORK, AND ALFRED HERRMANN, OF CHICAGO, ILLINOIS, ASSIGNEES TO ZUNNER MACHINES COMPANY, OF ROCHESTER, NEW YORK.

KEG-RINSER.

1,045,929.

Specification of Letters Patent.

Patented Dec. 3, 1912.

Application filed August 30, 1911. Serial No. 646,864.

To all whom it may concern:

Be it known that we, JOHN H. G. ZUNNER, a citizen of the United States, residing at Rochester, in the county of Monroe and State of New York, and ALFRED HERRMANN, a citizen of the German Empire, residing at Chicago, in the county of Cook and State of Illinois, have invented certain new and useful Improvements in Keg-Rinsers, of which the following is a specification.

This invention relates to keg-rinsers of the type in which a jet or spray of water, mingled with steam or air, is blown into the keg through the bung-hole.

The object of the invention is to provide a valve-mechanism, for such devices, of simple and efficient form, and particularly such a mechanism in which the steam or air is employed effectively to inject the water into the keg.

To the foregoing end the invention consists in the device hereinafter described, as it is defined in the succeeding claim.

The drawing illustrates a portion of a keg-rinser embodying valve-mechanism constructed in accordance with the present invention, the valve-mechanism and adjacent parts being shown in vertical section.

The illustrated embodiment of the invention is a keg-rinser in which the kegs are supported upon two rails 1, these rails being mounted upon standards or legs 2. A trough 3, carried by the rails, collects the water which runs from the kegs.

The part of the machine to which the present invention particularly relates is the valve-mechanism shown in section in the drawing. This mechanism is supported upon a web 35 forming a part of the frame 10 of the machine, and it comprises a valve-casing 23, of which the upper end is seated in a boss 37 in the web, being secured therein by a lock-nut 38. A nozzle 13 screwed in the upper end of the valve-casing is adapted to project through the bung-hole 14 of a keg Z.

The valve-casing 23 has an outlet-port, communicating directly with the nozzle 13, and two inlet-ports. The upper inlet-port 0 is supplied, through a pipe 16, with hot or cold water, the water being discharged into an upper chamber 15 of the casing. The lower inlet-port 22 is supplied, through a pipe 21, with steam or compressed air, the supply of the latter fluid being derived,

through a pipe 32, from any suitable source of supply and controlled by a hand-valve 33.

Within the valve-casing 23 is a vertically movable valve-stem 18 which carries, at its upper end, a valve 17 normally engaging a seat and closing the outlet-port, as shown in the drawing. Since the upper inlet-port is always open the chamber 15 is constantly filled with water under pressure, so that whenever the valve is drawn downwardly 65 from its seat water passes through the outlet-port and the nozzle 13. The lower inlet-port 22 is normally closed by the valve-stem 18. This stem is provided, however, with a central longitudinal passage 24 having a lateral inlet opening 25 at its lower end. When the valve-stem is sufficiently depressed, therefore, the opening 25 may be brought into register with the inlet-port 22, whereupon compressed air or steam flows through the 75 passage 24 and is discharged upwardly through the center of the outlet-port and through the nozzle 13.

A yoke 26 depending from the valve-casing 23 supports the lower end of a compression-spring 20, of which the upper end engages a nut 27 on the valve-stem. By the action of this spring the valve is normally held in closed position as illustrated. A pedal-lever 19 is pivoted, however, on a pin 28 at the lower end of the valve-stem, and one end of this lever is connected, by a link 29, with a member 30 of the frame of the machine. Accordingly, by depressing the other end of the pedal-lever, the valve-stem 85 may be drawn downwardly against the opposition of the spring 20. The first part of this movement causes the valve 17 to leave its seat, so that water alone is injected into the keg. By a further movement of the 90 pedal, air or steam is also introduced in the manner above described.

The valve-mechanism of the present invention not only provides for the admission to the keg at will, of water alone, or of a mixture of water and steam or compressed air, but it also provides for the efficient action of the latter in producing a powerful blast or spray. Owing to the position of the passage 24 in the middle of the valve 17, this passage discharges the air or steam directly into the middle of the stream of water passing through the nozzle, thus causing the nozzle to act as an aspirator in which the flow of water is powerfully assisted, while 110

the stream is effectually broken up into a spray in which the water and the air or steam are thoroughly mingled.

We claim:—

- 5 Valve-mechanism for keg-rinsers comprising, in combination, a spout adapted to discharge into a keg, a chamber having an outlet-port discharging into the spout and two separate inlet-ports, a spring-controlled valve normally adapted to close the outlet-port, a stem for the valve adapted to close one of the inlet-ports when the valve closes the outlet-port and longitudinally perforated to provide a duct adapted to discharge
- 10 15 directly into the spout and to make connection between the last mentioned inlet-port

and the spout, when the valve is moved from its seat, the other inlet-port being always uncovered, whereby connection is first made between the spout and the uncovered inlet only, and then between the spout and both said inlets, and means for so moving the valve-stem.

JOHN H. G. ZUNNER.
ALFRED HERRMANN.
